UNITED STATES PATENT OFFICE.

PAUL E. ERICKSON, OF COURTLAND, KANSAS.

IRRIGATING SYSTEM.

1,077,132.

Specification of Letters Patent.

Patented Oct. 28, 1913.

Application filed May 7, 1913. Serial No. 766,153.

To all whom it may concern:

Be it known that I, PAUL E. ERICKSON, a citizen of the United States, residing at Courtland, in the county of Republic and State of Kansas, have invented a new and useful Irrigating System, of which the following is a specification.

The present invention appertains to irrigating systems, and aims to provide a novel and improved means for supplying water from a stream to the trunks of irrigating systems along the banks of the stream.

It is also the object of the present invention to provide an apparatus of the character indicated which shall be simple, substantial and inexpensive in construction, as well as convenient and efficient in its use, and which shall eliminate the necessity of damming the stream.

Another object of the present invention is to provide a device of the nature indicated which shall also serve to strain the sand, and other extraneous matter, from the water so that the water may be discharged into the irrigating channels in a pure condition.

With the foregoing general objects outlined and with other objects in view, which will be apparent as the description proceeds, the invention resides in the combination and arrangement of parts and in the details of construction hereinafter described and claimed, it being understood that changes in the precise embodiment of the invention can be made within the scope of what is claimed without departing from the spirit of the invention.

The invention has been illustrated in its preferred embodiment in the accompanying drawing, wherein similar reference characters have been employed to denote corresponding parts, and wherein:-

Figure 1 is a perspective view of the improved apparatus, as in use, parts being broken away. Fig. 2 is a longitudinal section of one form of intake. Fig. 3 is a longitudinal section of another form of intake. Fig. 4 is a longitudinal section of a third variation.

In carrying out the invention, reference being had in detail to the drawing, there is provided a longitudinal water conduit or pipe 1, which may be of any desired length and diameter to suit the circumstances. The water conduit 1 is extended along the center of the river, creek or stream S and is arranged at a less angle or declination than

the stream. The length of the conduit 1 must be sufficient so that the head or upper end of the conduit may rest on the bed of the stream, while the foot or lower end of the conduit may extend above the banks B of the stream. The pipe 1 is disposed at a sufficient pitch in order that the water will flow readily down the conduit 1, it being observed that as the water flows down the conduit 1 the same will be raised with respect to the stream.

To the head of the water conduit 1, there is attached a lateral inlet pipe or manifold 2, and to the foot or lower end of the conduit 1, there are attached diverging branches 3. The inlet pipe or manifold 2 is adapted to rest on the bed of the stream, the said pipe extending from bank to bank or shore to shore, and the free ends of the branches 3 are designed to rest or project over the banks of the stream so as to discharge the water into the trunks or main channels I of the irrigating systems leading from the two banks. It will be observed that the free ends of the branches 3 resting upon the banks of the stream will support the lower end or foot of the conduit 1, while the other or upper end of the conduit will be supported by the lateral intake pipe or manifold 2, the said inlet pipe or manifold extending between the banks of the stream so as to prevent lateral motion of the conduit. It will be evident that the conduit 1 may be extended sufficiently upstream in order that when the free ends of the branches 3 rest on the opposite banks of the stream, the intake pipe or manifold 2 will lie in a plane above the free ends of the branches 3, or in order that the conduit 1 will have a sufficient inclination from its lower end to its upper end.

Supplemental diagonal pipes 5 are attached to the conduit 1 at points slightly below the inlet pipe 2 and are attached at their other ends to the inlet pipe or manifold at points between its ends and intermediate portion, the inlet pipe or manifold 2 being attached at its intermediate portion to the upper end or head of the conduit 1. The pipes 5 not only assist in carrying the water from the end portions of the intake pipe or manifold 2 to the conduit 1, but also brace the pipe in position.

The inlet pipe or manifold 2 is provided with a series of openings 6 in the top thereof, the openings being disposed at intervals

throughout the length of the pipe 2, and screens 7 of sufficiently fine mesh are secured over the inlet openings 6, in order to strain the water admitted through the said 5 openings.

Rubber or flexible tubings 8, 8' and 8'' are attached to the upstream side of the pipe 2 at intervals along the length of the pipe, and extend upstream, each of the said tubings having a water chamber or compartment attached to its free end. These water chambers or compartments may be of various designs. Thus, the water chamber may be in the form of an open ended cylinder 15 9 having its ends provided with screens 10, the tubing 8 being engaged through one side of the cylinder or casing. The water chamber may also be in the form of a cylinder 9' having one end open to receive the tubing 20 8', the cylinder 9' having the apertures or openings 6', and a tubular screen 7' embracing the cylinder 9' to strain the water prior to admission through the openings 6'. As shown in Fig. 4, the water chamber embodies two convexed sides 9'' having the 25 openings 6'' therein, screens 7'' being secured over the openings 6'', and the tubing 8'' being passed through the edge of the water chamber. Either or all of these forms 30 of water chambers may be employed, it being noted that they are flexibly connected to the intake pipe or manifold 2, by means of the flexible tubings, so that they may vibrate or swing under the conditions to 35 which they are subjected when immersed in the stream.

From the foregoing, taken in connection with the drawing, it will be evident that the present apparatus may be readily set in 40 place, the length of the conduit 1 being adjusted according to the slope of the stream and the height of the banks B. The water admitted into the inlet pipe or conduit 2 will be strained, it being observed that the 45 water chambers or compartments are free to flex or vibrate, to prevent clogging, the water flowing down the conduit into the branches 3, from whence the water is discharged into the trunks or main channels or 50 ditches I of the irrigating systems extending from the two banks B of the stream S. The branches 3 are preferably provided with valves 4 adjoining their free ends, in order that the flow of water into the respective channels I may be regulated or shut off.

The present apparatus may not only be employed for purposes of irrigation, but may be also utilized for other purposes,

such as for water power, the water flowing from the discharge branches 3 being utilized 60 to drive water wheels or kindred appliances.

From the foregoing, taken in connection with the drawings, the advantages and capabilities of the present invention will be apparent to those versed in the art, it being 65 observed that the objects aimed at have been carried out satisfactorily, and that the present device provides a desirable one for the purposes for which it is designed.

Having thus described the invention, what 70 is claimed as new is:—

1. In a system of the character described, a longitudinal water conduit designed to extend along and at a less angle of declination than a stream, a lateral inlet pipe attached 75 to the head of the conduit to rest on the bed of the stream, the inlet pipe having inlet openings along its length, and diverging branches attached to the foot of the conduit, the free ends of the branches being designed 80 to rest on the banks of the stream and to discharge the water into the irrigating trunks.

2. In a system of the character described, a longitudinal water conduit designed to extend along and at a less angle of declination than a stream, a lateral inlet pipe attached 85 at an intermediate point to the head of the conduit to rest on the bed of the stream, supplemental diagonal pipes connecting the 90 conduit and inlet pipe, and diverging branches attached to the foot of the conduit, the free ends of the branches being designed to rest on the banks of the stream and to discharge the water into the irrigating trunks. 95

3. In a system of the character described, a longitudinal water conduit designed to extend along and at a less angle of declination than a stream, a lateral inlet pipe attached 10 to the head of the conduit to rest on the bed of the stream, flexible tubings attached to the inlet pipe at intervals along its length and projecting upstream, water chambers attached to the free ends of the tubings and having screened openings, and diverging 15 branches attached to the foot of the conduit, the free ends of the branches being designed to rest on the banks of the stream and to discharge the water into the irrigating trunks. 11

In testimony that I claim the foregoing 11 as my own, I have hereto affixed my signature in the presence of two witnesses.

PAUL E. ERICKSON.
